RUDOLF DOHNALEK, OF CHICAGO, ILLINOIS

ALARM-CLOCK MECHANISM

Application filed August 8, 1929. Serial No. 384,294.

This invention relates to time controlled means for closing and opening electric circuits and has special reference to a combined circuit controller and alarm.

5 The ordinary alarm clock is used to arouse people in the morning and in many cases it is necessary for a person using such clock to set the alarm at an earlier hour than they desire in order that they may have time to 10 prepare coffee or other articles for their breakfasts. With the advent of modern electrical apparatus, as for instance coffee percolators, one has to arise from fifteen or twenty minutes before they desire in order 15 to turn on the electricity for the percolator or other like electrical cooking device. Also, in working around a house the housewife frequently wishes to cook a certain article for a definite length of time and to remove the 20 article from the stove at the expiration of such time so that it may immediately stop cooking. In her work around the house the housewife sometimes forgets to note the time which has elapsed and article being cooked 25 is burnt or otherwise spoiled.

The principal object of the present invention is to provide, in connection with an ordinary alarm clock suitable for sounding an audible alarm, circuit controlling means so 30 arranged as to close a circuit at a predetermined time before the sounding of the alarm and to simultaneously open the circuit and sound the alarm at the desired time.

A second important object of the invention 35 is to provide simple and efficient means by which the circuit closer may be actuated.

A third important object of the invention 40 is to provide simple means for setting the circuit closer to close the circuit at any desired time.

With the above and other objects in view as will be hereinafter apparent, the invention consists in general of certain novel details of construction and combinations of 45 parts hereinafter fully described, illustrated in the accompanying drawings and specifically claimed.

In the accompanying drawings like characters of reference indicate like parts in the 50 several views, and;

Figure 1 is a face view of an alarm clock constructed in accordance with this invention.

Figure 2 is a rear view thereof.

Figure 3 is a detail elevation of that portion of the clock mechanism controlling the circuit closer, the view also showing the circuit closer and adjacent parts. 55

Figure 4 is a section on the line 4—4 of Figure 3. 60

Figure 5 is a detail section on the line 5—5 of Figure 3.

Figure 6 is a detail section on the line 6—6 of Figure 4.

Figure 7 is a view similar to Figure 4 but 65 showing the switch in open position.

Figure 8 is a wiring diagram of the invention.

As shown in Figure 1 there is disclosed an alarm clock of the ordinary round type having a casing 10, a time dial 11 and an alarm set hand 12 which is operated from the rear by a turning head 13 so that the alarm may be set in the usual manner for any particular time it is desired that it be sounded. The 70 clock is also, of course, provided with the usual hands 14. Now, all of these parts, together with the time train and alarm train (not shown) are those common to any alarm clock and accordingly it is not deemed necessary in this specification to go into a detailed description of the various wheels, staffs and other parts of the common and ordinary alarm clock mechanism with which this invention is adapted to be used, it being merely 75 necessary to a complete understanding of the invention to set forth those parts which are in direct connection with the circuit closing mechanism. 80

Now, referring to Figure 5 there is there indicated the hour wheel 15 of the usual clock-work and driven by this hour wheel is an idler pinion 16 which meshes with the main wheel 17 of the circuit closer timing device and this main wheel is fixed on a sleeve 18 which is mounted on a staff 19 journaled in the frame plates 20 of the clockworks. On the forward end of this staff 19 is mounted the alarm set hand 12. On the rear end of the sleeve 18 is fixed a disk 21 which disk acts 85

100

as a checking device for holding the circuit closer open as will be hereinafter set forth. On the front side of the wheel 17 there is mounted an edge cam 22 having a notch 23 therein and through the staff 19 extends a pin 24. A compression spring 25 is mounted on the staff 19 between the rear frame plate and the disk 21 and urges the disk and cam forwardly, these parts being held against forward movement until the notch 23 is in position in alinement with the pin 24 at which time the sleeve 18 and the parts attached thereto move forwardly under the influence of the spring 25. It will be noted that this cam arrangement for tripping the circuit closing device at the proper time is substantially that employed in many alarm clocks for tripping the alarm circuit. Behind the rear plate of the casing the staff 19 carries a knurled head 26 for setting the pin to the desired time as indicated by the position of the hand 12 and a spring 27 is used as friction means to restrain the staff from accidental turning. Mounted adjacent the staff 19 is a circuit closer staff 28 whereon is mounted a disk 29 to which is connected one end of a coiled winding spring 30, the other end of said spring being fixed to the staff 28 so that rotation of the staff winds the spring. Fixed to the disk 29 to revolve therewith is a disk 31 of insulating material and this disk carries a conductor strip 32 so that the disk forms a rotary contact maker to bridge, when in closed position, the brushes 33 and 34 with which the circuit closer is connected to the remainder of the apparatus. Extending from the disk 29 is an arm 35 which is positioned to engage against the check member or disk 21 when the latter is in its rearward position as shown in Figure 6 but which is freed from such engagement when the disk moves forwardly. Also, the disk 29 carries a finger 36 which engages with the main wheel 37 of the alarm train, this wheel being mounted on a winding staff 38 and driven by the unwinding of the alarm spring 39 upon tripping of the alarm train. As before noted the remainder of the alarm device is not deemed necessary to be shown.

As shown in Figure 8 the line wire connections 40 are plugged into the sockets 41 of the usual type mounted on the case 10. From one of these sockets a wire 42 leads to the contact 34. Also there is provided a second pair of sockets 43 adapted to receive the lead wires 44 for connecting the clock to any suitable electric mechanism here indicated by the heating resistance 45 which may be taken as typical of the resistance in a percolator, stove or the like. One of the connections 43 is connected by a wire 46 with the brush 33 while the other connection 43 is connected by a wire 47 with the remaining connection 41.

In operation the alarm proper is set at

the time the person desired to rise or to perform some other duty, this also being the time at which it is desired to turn off the closed circuit. The hand 12 is then set to the time at which it is desired to turn on or close the circuit. The winding button or head 48 is manipulated to wind the spring 30. Now, under these circumstances the finger 35 will engage the disk 21 and the parts will be in the position shown in Figure 7 with the circuit open. Upon the time for closing the circuit having arrived the notch 23 will be alined with the pin 24 and the disk 21 will move forwardly to free the finger 35 so that the disk 29 will rotate under the influence of the spring 30 until the finger 36 engages the teeth of the wheel 37. At this time the parts will be in the position shown in Figure 4 and the circuit will be closed. The circuit will then remain closed until the audible alarm train is tripped whereupon the wheel 37 will revolve and turn the disk 29 to free the finger 36, the disk 29 rotating further under the influence of the spring 30. Meanwhile, the cam 22 has rotated to move the disk 21 forwardly so that the finger 35 again contacts with the disk 21 and the circuit closer is stopped in open circuit position.

Obviously, this circuit closer may be used in connection with a wide variety of devices and the invention is not confined solely to percolators but the same alarm may be used for turning on and off lights, setting and opening burglar alarm systems and has many other applications as will be apparent to any skilled electrician.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In an alarm clock, a circuit closer for an electric circuit and including a rotary contact carrying member, means urging said member to rotate, a stop member projecting from the rotary member to rotate therewith, an alarm train including a member wherewith said stop engages upon the contact member moving to closed position, said alarm train member moving to free the stop and permit rotation of the contact member to open circuit position upon tripping of the alarm, and time controlled mechanism normally holding the contact member in open circuit position and acting to free the

- said member for closing the circuit at a predetermined time.
2. In an alarm clock, a circuit closer for an electric circuit and including a rotary contact carrying member, a manually wound spring urging said member to rotate, a stop projecting from the rotary member to rotate therewith, an alarm train including a stop engaging member engaging the stop upon the contact member moving to closed circuit position and checking further rotation of said contact member, said alarm train member moving to free the stop and permit rotation of the contact member to open circuit position upon tripping of the alarm train, and a time controlled element in the path of said stop to check the stop in open circuit position and movable at a predetermined time to free the stop and permit its movement to engage the alarm train member.
3. In an alarm clock, a circuit closer for an electric circuit and including a rotary contact carrying member, a manually wound spring urging said member to rotate, a stop projecting from the rotary member to rotate therewith, an alarm train including a wheel having means wherewith the stop engages and rests upon the contact member moving to circuit closing position, the rotation of said wheel upon tripping of the alarm train freeing said stop to permit further rotation of said contact member, and a time controlled element in the path of said stop to bring the contact member to rest in open circuit position and movable at a predetermined time to free the stop and permit its movement to engage said wheel means.
4. In an alarm clock, a circuit closer for an electric circuit and including a rotary contact carrying member, a manually wound spring urging said member to rotate, a stop projecting from the rotary member to rotate therewith, an alarm train including a wheel having means wherewith the stop engages and rests upon the contact member moving to circuit closing position, the rotation of said wheel upon tripping of the alarm train freeing said stop to permit further rotation of said contact member, a slidably movable check member normally positioned to be engaged by said stop in open circuit position of the contact member, a spring urging said check member out of the path of said stop, and time controlled means normally restraining said check member from movement by said spring and arranged to free the check member for movement at a predetermined time.
5. In an alarm clock, a circuit closer for an electric circuit and including a rotary contact carrying member, a manually wound spring urging said member to rotate, a stop projecting from the rotary member to rotate therewith, an alarm train including a stop engaging member engaging the stop upon the contact member moving to closed circuit position and checking further rotation of said contact member, said alarm train member moving to free the stop and permit rotation of the contact member to open circuit position upon tripping of the alarm train, a slidably movable check member normally positioned to be engaged by said stop in open circuit position of the contact member, a spring urging said check member out of the path of said stop, a cam driven by the clock to rotate in unison therewith, said cam having said check member fixed thereto, and a pin engaged by said cam and manually movable to time the release of the check member, said cam having a low point resting on the pin to effect said release.
6. In an alarm clock, a circuit closer for an electric circuit and including a rotary contact carrying member, a manually wound spring urging said member to rotate, a stop projecting from the rotary member to rotate therewith, an alarm train including a wheel having means wherewith the stop engages and rests upon the contact member moving to circuit closing position, the rotation of said wheel upon tripping of the alarm train freeing said stop to permit further rotation of said contact member, a slidably movable check member normally positioned to be engaged by said stop in open circuit position of the contact member, a spring urging said check member out of the path of said stop, a cam driven by the clock to rotate in unison therewith, said cam having said check member fixed thereto, and a pin engaged by said cam and manually movable to time the release of the check member, said cam having a low point resting on the pin to effect said release.
- In testimony whereof I affix my signature.
- RUDOLF DOHNALEK.
